Original application July 1, 1942, Serial No.
449,324. Divided and this application Decem-
ber 27, 1946, Serial No. 718,729

2 Claims. (Cl. 102—79)

(Granted under the act of March 3, 1883, as
amended April 30, 1928; 370 O. G. 757)

1

This invention relates to improvements in fuzes for explosive projectiles, and the instant disclosure thereof is a division of an application for United States patent on Fuzes, filed by Raymond L. Graumann and William J. Donahue, Jr., July 1, 1942, Serial No. 449,324, now Patent No. 2,427,671.

A nose fuze such as the instant device is, comprises an explosive-loaded instrument for igniting or detonating the explosive filler of the projectile which carries it. Said fuze is of the point-detonating type and it is intended to function by igniting the burster charge or explosive filler on impact with the target. Because of the sensitivity of the elements of the explosive train in the nose fuze, it is necessary to embody adequate safety features in order to forestall serious accidents during the transportation of projectiles, loading ammunition on board ships, loading projectiles into guns and, especially, while the projectile is subjected to the sudden and violent forces of being fired from the gun.

The safety features incorporated in the instant fuze render it both bore safe and detonator safe. That is to say, the fuze is immune to becoming armed in case the projectile encounters an obstruction in the bore of the gun, hence will not cause a bore detonation. It is detonator safe because its construction is such that should the detonator be set off for any reason while the fuze is in the unarmed condition, the booster charge of the fuze, hence the explosive filler, will not be detonated.

These safety features are obtained by maintaining a break in the continuity of the explosive train of the fuze until the projectile actually begins its flight from the muzzle of the gun. Thereupon the centrifugal force developed by the spinning of the projectile becomes effective to establish the continuity of the explosive train, in other words to arm the fuze, in readiness for the firing thereof when the projectile strikes the target.

Therefore, one of the objects of the invention is to provide a nose fuze which is contrived to insure the deferment of registration of the components of the explosive train with the firing pin or its equivalent, until the projectile is subjected to centrifugal forces such as will ordinarily be developed therein only upon firing said projectile from a gun.

Another object of the invention is to provide a fuze of the type known as supersensitive, that is to say, a fuze which is sufficiently delicate in its response to insure its functioning upon striking

the lightest and most fragile targets, for example, the fabric of an airplane.

Another object of the invention is to provide a fuze with a comparatively fragile nose, which 5 fragility insures its ready yielding or collapse when striking a target offering appreciable resistance to penetration.

A further object of the invention is to provide a 10 nose fuze which is characterized by a yoke spring which arrests the firing pin until the instant of impact with the target, said yoke spring initially abutting a shoulder to accomplish that purpose, and then during flight when spread out of contact with the shoulder by the centrifugal action 15 of the rotor detents, persisting in said function of arresting the firing pin by the friction factor between the yoke spring and fuze cover.

Other objects and advantages will appear in 20 the following specification, reference being had to the accompanying drawing in which:

Fig. 1 is a longitudinal section of the nose fuze, showing the parts in the static position assumed prior to flight;

Fig. 2 is a horizontal section of the nose fuze, 25 taken substantially on the line 2—2 of Fig. 1, and

Fig. 3 is a view similar to Fig. 1, illustrating the 30 fuze in the firing position, parts being shown in elevation.

In carrying out the invention provision is made 35 of a fuze 25 which has a body 26 with a base 27 at the aft end. The base 27 is externally threaded at 28 for screwing into the nose of an explosive projectile. The body 26 includes a boss 29 at the forward end, the base and boss comprising a single metal piece which has the following characteristics.

A cavity 30 in the base 27 contains the booster charge 31, the latter being held in place by a closure 32 and a marginal crimp 33. A bore 34 40 contains a lead-in 35, usually composed of the same substance as the entire explosive train, namely Tetryl. As seen in the drawings, the bore 34 communicates at its aft and forward ends respectively with the cavity 30 and with a chamber 36. Said chamber comprises a kerf which is cut in from the point of the fuze boss 29. The forward part of it takes in the entire ogive as seen in Fig. 2, ending at walls 37 which can be identified as extensions. From there on back the 45 chamber has a semi-circular contour 38, the axis 39 thereof being set back a little way from the common face of the walls 37 so as to delineate two flat terminals 40. These terminals join the walls 37, are tangential to the contour 38 and, usually, 50 are parallel to each other.

Another object of the invention is to provide a fuze of the type known as supersensitive, that is to say, a fuze which is sufficiently delicate in its response to insure its functioning upon striking

The chamber 36 also has plane walls 41 (Fig. 1). These confront each other, and extend forwardly and outwardly to complete the identity of the kerf mentioned at the beginning. The circular part of the chamber 36 forms an adequate pocket for the detonator-carrier or rotor, presently described in detail, and the rotor may freely do such turning in the chamber as will be required of it in the flight of the projectile and fuze.

A circular hole 42 is bored in from the point of the boss 29, intersecting the kerf of the chamber 36. Said hole constitutes a yield-opening into which the circular pad of the firing pin recedes under point-pressure. The axis of the chamber 36 is perpendicular to the axis of the fuze and is at right angles thereto. Alined bores 43 intersect the chamber 36 in an off-center position with reference to the rotor, the outer and back parts thereof at 44 functioning as shoulders. The bores emerge at the exterior of the ogive where the surface of the boss 29 is slotted across the bores on opposite sides of the boss 29 to provide passageways 45 which start at the point and extend back almost to a circular wall 46 near which the thread course 28 ends.

The passageways 45 intersect the outer ends of the bores 43, the latter thus dividing the passageways into long and short components 47 and 48 which, respectively, are occupied and occupiable by the free ends of the yoke spring in the manner presently explained. A cover 49 is ultimately applied to the fuze boss 29, fitting the ogive very tightly and being spun at 50 behind the circular wall 46 to insure its staying in place. The forward-end of the cover has an opening 51 which is delineated by an inturned rim 52 of the cover. This rim serves as a stop flange for the circular pad of the firing pin.

Specific reference is now made to parts previously mentioned but deferred as to description. The rotor 53 which is a circular disk, has a turning fit in the kerf 38 of semicircular contour. It has recesses 54 in its plane faces on opposite sides. When these are occupied by the pin ends 55 of the detents 56 the rotor is prevented from turning. Under that circumstance the rotor is in its unarmed position, and the relationship of the recesses 54 to the cross-bore 57 in the rotor is such that the detonator 58 contained by the cross-bore will be out of registration with the axis of the fuze, hence both bore safe and detonator safe.

Since the turning of the rotor cannot occur until the projectile has left the muzzle, there is no way in which the bursting charge could be ignited because the rotor remains locked in place as long as there is a lack of sufficient centrifugal force to displace the detents 56. Since the degree of centrifugal force required is not acquired while the projectile is still traveling the barrel, it follows that the detonator will remain in its biased position (Fig. 2). The fuze is thus rendered bore safe, and if by any chance the detonator 58 should be set off, the same biased position of the detonator would keep the flash from the rest of the explosive train, thus rendering the fuze detonator safe. The detents 56 are in the form of cylindrical or otherwise cross-sectionally formed plugs, the outer or butt ends of which are desirably rounded at 59 as shown. The rotor is lead-weighted at 53a to cause rotor-turning under centrifugal force to arm the fuze.

The yoke spring 60 comprises a central, round plate 61 from opposite sides of which the spring arms 62 diverge. The places where the arms join

the plate comprise rounded heels 63 which have bearing against the contiguous parts of the cover 49. The bearing involves enough pressure from the cover to keep the spring arms flexed inwardly toward the axis of the fuze, down against the rounded butts or the detents and in line with the shoulders 44 for contact with which the arm ends 64 are given a bend. These bends are perpendicular to the axes of the detents and therefore exercise an axially centered thrust inwardly upon the detents, keeping them seated and centered truly in their bores 43 and upon the rotor.

In making the yoke spring 60 the arms 62 are given the U-shape shown with reference to the plate 61, with an initial tendency to bear down on the detents when slipped into place. Such inwardly directed tension as the arms have is augmented by the pressure of the cover 49 on the heels 63 when the final assembly is made. The arms 62 fit the passageways 45 loosely, and it is in these passageways that the arms flex outwardly by centrifugal force impressed both on the detents and on the arms leading up to the assumption of the final position in Fig. 3.

An opening 65 in the center of the plate 61 contains the shank of the firing pin 66, a part of the shank being swaged over the plate. The pin projects from a base pad 67 against which the plate 61 is held immovably by the swaging. The rim of the disk is adapted to ride the wall of the hole 42 as the firing pin moves to the firing position. The disk 67 comprises part of the point seal of the fuze, its perimeter being rabbeted at 68 to define an annular seat for the rim 52 of the cover. The previously mentioned pressure of the cover on the heels 63 reacts to force the disk or pad 67 to its farthest forward position and into sealing engagement with the rim 52.

The operation of the fuze is readily understood. Figs. 1 and 2 illustrate the dormant condition of the fuze, in other words, the condition of the parts after assembly and up to the time of firing. The detonator 58 assumes the biased position shown in Fig. 2, that is, biased with respect to the firing pin 66 and longitudinal axis of the fuze. It is locked there by the pin ends 55 of the detents 56. The detents are held in the locked positions and in their bores 43 by the yoke spring 60, the ends 64 of which are braced against the shoulders 44.

After cessation of the set-back force upon firing the projectile, centrifugal force causes the detents 56 to move outwardly, withdraws the pin ends 55 from the rotor recesses 54 and spreads the yoke spring outwards against the cover 49, thereby displacing the ends 64 from the shoulders 44. Since the rotor is now free to turn or arm, the weights 53a line up across the fuze, moving the detonator 58 into alignment with the lead-in 35, thus completing the explosive train.

The firing pin 66 remains in its forward position during the flight of the projectile, due to friction between the rear tips of the ends 64 of the yoke spring and cover. These tips are driven against the cover by the force of the centrifugally actuated detents 56, and the pressure thereof is sufficiently great to prevent the premature inward displacement of the firing pin pad 67 due to air pressure. In striking the target, the firing pin and the yoke spring are driven rearwardly with reference to the fuze, then assuming the position shown in Fig. 3. The yoke spring is guided in the long slot components 47, the short components 48 providing external reliefs or recesses for the entry of the ends 64 in the final position of the

yoke spring. The stabbing of the detonator 58 by the firing pin initiates the explosive train.

The invention herein described may be manufactured and used by or for the Government of the United States of America for governmental purposes without the payment of any royalties thereon or therefor.

We claim:

1. In a fuze, a body having a keif providing a chamber and having radial bores extending from the chamber, a portion of each bore forming a shoulder, a detonator-carrier turnably mounted in the chamber, detent means occupying the bores and holding the carrier in an initially unarmed position, a firing pin to explode the detonator, and a spring yoke carrying said firing pin, said yoke having arms superimposed upon the detent means to hold them in the bores and having tips engaging the shoulders to brace the yoke in position to hold the firing pin in the forward position.

2. In a fuze, a body having a detonator carrier-chamber and having bores extending radially from the chamber, detonator carrier detent means radially movable in the bores, means to restrain the detent means consisting of a base

pad, a yoke affixed to the base pad and having spring arms with rounded heels formed by bends at which the spring arms extend away from the base pad toward and over the outer ends of the detent means, and a cover fitted on the body, bearing on the heels to flex the arms inwardly toward the axis of the fuze.

RAYMOND L. GRAUMANN.
